COMBINED RAZOR AND SHARPENING DEVICE

Ray L. Burchett, Newark, N. J., assignor to Art Metal Works, Inc., a corporation of New Jersey

Application January 16, 1942, Serial No. 426,939

18 Claims. (Cl. 30—36)

My invention relates to a combined razor and sharpening device.

My invention has particular reference to a combined razor and sharpening device embodying novel means for holding the razor blade either in shaving or sharpening position.

My invention relates more particularly to a combined razor and sharpening device wherein the razor blade is of the single-edge type, means being provided for causing either side of the edge of the razor blade to engage a sharpening device or to be located in shaving position.

My invention has further reference to a novel arrangement for varying the inclination of a razor blade when in shaving position.

Still further, my invention relates to a novel and advantageous arrangement for mounting the sharpening roller forming part of a device of the character stated.

Various other objects, advantages and features of my invention will become apparent from the following detailed description.

My invention resides in the combined razor and sharpening device, features and combinations of the character hereinafter described and claimed.

For an understanding of my invention and for an illustration of one of the forms thereof, reference is to be had to the accompanying drawing, in which:

Figure 1 is a rear elevational view, partly in section, showing the razor arrangement of my invention;

Fig. 2 is a side elevational view of the razor arrangement shown in Fig. 1;

Fig. 3 is a horizontal sectional view, partly in plan, taken on the line 3—3 of Fig. 1;

Fig. 4 is a horizontal sectional view taken on the line 4—4 of Fig. 1 looking in the direction of the arrows;

Fig. 5 is a plan view showing the supporting frame for the razor arrangement of my invention;

Fig. 6 is an enlarged vertical sectional view, partly in elevation, taken on the line 6—6 of Fig. 2 looking in the direction of the arrows;

Fig. 7 is a vertical sectional view, partly in elevation, taken on the line 7—7 of Fig. 5;

Fig. 8 is a vertical sectional view, partly in elevation, showing one form of mechanism for mounting a razor blade in its supporting yoke; and

Fig. 9 is an elevational view showing a modification of the invention.

Referring particularly to Fig. 1, a tubular member 1 is shown as having a cylindrical gripping

member 2 formed integrally therewith. Beyond the member 2, the upper end of the tubular member 1 merges into a frame 3 which, when the razor is positioned vertically as shown in Fig. 1, comprises a horizontal plate surface 4, vertical side plates 5 and 5, and a plane vertical plate 6 disposed between and joining said plates 5, 5. One plate 5 has a pair of ribs 7, 7a extending therefrom and the other plate 5 has a similar pair of ribs 8, 8a extending therefrom, the ribs of each pair extending toward each other and being disposed in transverse alignment, respectively, Fig. 5. The ribs 7, 7a and 8, 8a form a pair of notches or recesses 9 which open upwardly and are disposed in transverse alignment for a purpose hereinafter to be described.

Extending freely through a passage provided therefor in the tubular member 1 is a rod 10 which is secured to a handle sleeve 11 having a knurled or roughened outer surface. A spring 12 coiled around the rod 10 applies opposite forces to the tubular member 1 and the associated handle sleeve 11 tending to separate them.

The rod 10 is circular in cross section and, at 13, said rod 10 merges into a rod 14 which is square in cross section, the square rod 14 being freely slidable in a passage 15 of corresponding shape provided in the frame 3, Fig. 5, and extending, to predetermined extent, downwardly into the tubular section 1 where it merges with the passage provided in said tubular member 1 for the slidable reception of the rod 10.

The square end of the rod 14 terminates in a U-shaped yoke 16 freely slidable in a vertical direction at one side of the hereinbefore described plate 6. As indicated in Fig. 8, each vertical arm of the yoke 16 is provided with a horizontal passage 16a, the passages 16a being transversely aligned for the reception of the respective locking pins or detents 17 and 18. As shown in Fig. 8, the detent 17 comprises a stem 17a which is freely slidable in a passage formed in a stem 18a of the detent 18. A helical spring 19 confined within said last named passage biases the detents 17 and 18 from each other. Each of the detents 17 and 18 has a laterally extending pin 20 and each pin 20 is movable into a slot formed in the adjacent arm of the yoke 16.

As indicated in Fig. 1, the razor blade 21 is formed with arms 21a disposed at opposite ends of the rear side thereof and extending rearwardly from the cutting edge of the blade, each blade arm 21a being provided with a passage 21b extending parallel with respect to said cutting edge of the blade. The distance between the inner,

facing surfaces of these arms **21a** is only slightly greater than the distance between opposite, exterior surfaces of the yoke arms. Hence, the blade **21** may be positioned, as shown in Figs. 1 and 8, with the blade arms **21a** disposed exteriorly of or embracing the respective yoke arms and with the passages **21b** thereof alined with respect to the respective passages **16a** of the yoke arms.

In Figs. 1 and 8, the blade **21** is shown as attached to the arms of the yoke **16** by the detents **17** and **18** which, under the influence of the spring **19**, are biased from each other to the extent permitted by the pins **20** as the latter are seated in the respective slots provided therefor in the yoke arms **16**. As shown in Fig. 8, the detent **17** comprises a stem **17a** which freely extends into a passage provided therefor in the shank **18a** of the detent **18**. When thus positioned, the razor blade **21** may be oscillated on and with respect to the arms of the yoke **16**. When it becomes desirable to remove the blade **21** from the yoke **16**, the pins **20**, either individually or jointly, are manually engaged and moved toward each other to an extent sufficient to cause disengagement thereof from the respective slots in which they had been seated whereupon said pins **20** are moved circumferentially out of alinement with their respective slots. This operation entirely removes the ends of the detents **17** and **18** from the respective passages **21b** of the razor blade and effectively holds said detents in their disengaged position. When this has been done, the razor blade **21** may be removed from the yoke arms. Conversely, it will be understood that said razor blade **21** may be attached for free oscillatory movement to the yoke arms, after the passages **21b** thereof have been alined with the respective detents **17** and **18**, by partially rotating said detents so that they may be seated in the razor blade passages **21b** under the influence of the spring **19**.

Although I have shown a present preferred arrangement for attaching and detaching a razor blade to or from the arms of the yoke **16**, it will be understood that various other equivalent arrangements may be utilized in lieu thereof as desired.

As indicated particularly in Figs. 1 and 2, the yoke **16** comprises oppositely extending ledge sections **16b** adapted, in the manner hereinafter described, to be disposed within the respective recesses **9** when the razor blade **21** is either in shaving position or in sharpening position.

The blade **21**, when in shaving position, has its shaving or cutting edge disposed adjacent a guard **22** fixed between the aforesaid side plates **5** and **5**, the guard **22**, preferably, being provided with teeth **22a** which face the razor blade cutting edge. Disposed flatwise against the plane plate **6** and mounted for oscillatory movement on a pin **23** projecting therefrom is a cam member **24** having an actuating handle **24a**, the ends of which are movable between stop pins **25** mounted on and extending from the aforesaid plate **6**.

With the razor blade **21** in the position shown in Fig. 2, it will be understood that the cam member **24** may be swung in one direction or the other to thereby cause the cutting edge of said blade **21** to take a desired cutting position with respect to the guard **22**. The cam member **24** is frictionally or otherwise so controlled that it remains stationary in any desired position to which it is adjusted, the degree of friction, however, being insufficient to prevent ready manual movement of said cam member **24** on its supporting pin **23**.

In accordance with the invention, each of the

plates **5**, **5** carries a tubular housing **26** and these housings **26** are disposed in transverse alinement with each other. The outside wall surface of each of the housings **26** is provided with slot **26a**, the slots **26a** being disposed in transverse alinement with each other and with similar slots **5a** formed in the respective plates **5**, **5**. Each set of the slots **5a** and **26a** receives a pintle **27a** of a blade sharpening roller **27**. As shown in Fig. 6, each pintle **27a** is engaged by a member **28** biased in an upward direction by a spring **29**, the member **28** and spring **29** being confined within the associated housing **26**.

The slots **5a** and **26a** extend in a direction extending substantially at right angles to the plane of the razor blade **21** when the latter is in sharpening position, i. e., when the cutting edge thereof is in engagement with the sharpening roller **27**. Therefore, as hereinafter more fully described, the roller **27** is free to automatically take a more effective sharpening position than would be the case were said roller **27** rotatable on a fixed longitudinal axis.

The razor blade **21**, on each side thereof, is provided with a slot or recess **21c**, these recesses being transversely alined and so arranged that, when said razor blade **21** is in engagement with the sharpening roller **27**, the above described ribs **7a**, **8a** of the frame **3** are received within the respective slots **21c** and the side face of the rear portion of the razor blade **21** rests on top of the above described ribs **7**, **8** of said frame **3** whereas, when the razor blade **21** is in shaving position, the ribs **7**, **8** are received within the respective recesses **21c** and the side face of the rear portion of said razor blade **21** rests on top of the ribs **7a** and **8a**, Fig. 2.

In Fig. 2, the razor blade **21** is shown as disposed in shaving position. When thus disposed, the spring **12** holds the yoke **16** toward the plate surface **4** of the frame **3** and maintains the yoke sections **16b** within the respective frame recesses **9**. However, the spring **12** is prevented from seating any of the yoke surfaces in engagement with the frame surfaces last described by reason of the motion-limiting effect on the razor blade **21** produced, first, by the ribs **7a** and **8a** which are engaged by the side face of the rear portion of the razor blade **21** and, second, by the cam member **24**, which is engaged by an intermediate surface of said razor blade **21**.

As will readily be understood from a consideration of Fig. 2, the described action of the spring **12**, acting through the yoke **16**, draws the side face of the rear portion of the razor blade **21** into engagement with the ribs **7a**, **8a** whereby a biasing effect is applied to said razor blade **21** tending to rotate the same in a clockwise direction, Fig. 2, to an extent permitted by the cam member **24** whereby the outer or cutting edge of said razor blade **21** is positively held in shaving position. At this time, the ribs **7**, **8** extend freely within the respective recesses **21c** of the razor blade **21**.

When it becomes desirable to change the shaving position of the razor blade **21**, the cam member **24** may be moved in one direction or the other to thereby change the inclination of said razor blade **21** and vary the position of the cutting edge thereof with respect to the guard **22**.

When the razor blade **21** is to be sharpened, the yoke **16** is elevated, against the action of the spring **12**, by effecting relative movement toward each other of the circular gripping section **2** and the handle sleeve **11**, the movement last named

being continued until the square rod 14 has been moved from the square passage 15. After the operation last noted has been completed, the yoke 16 may be rotated with respect to the tubular member 1 and the frame 3 through an angle of 180 degrees while holding the handle sleeve 11 stationary and rotatably moving the gripping member 2. Thereupon, the holding pressure on the spring 12 may be released to produce downward movement of the yoke 16 so that the latter descends into its normal position adjacent the frame surface 4 with the yoke sections 16b disposed within the respective frame recesses 9. In so doing, the cutting edge of the razor blade 21 comes into engagement with the sharpening roller 27 which may be rotated in suitable manner to thereby effect the desired sharpening action.

When the razor blade 21 is thus disposed in sharpening position, Fig. 1, the spring 12 draws the yoke 16 toward the plate surface 4 of the frame 3 and maintains the yoke sections 16b within the respective frame recesses 9. However, the spring 12 is prevented from seating any of the yoke surfaces in engagement with the frame surface last described by reason of the motion-limiting effect on the razor blade 21 produced, first, by the ribs 7, 8 which are engaged by the side face of the rear portion of said razor blade 21 and, second, by the surface of the sharpening roller 27 which is engaged by the front surface of the razor blade.

In generally the same manner as previously described, the spring 12, acting through the yoke 16, draws the rear surface of the razor blade 21 into engagement with the ribs 7, 8 whereby a biasing effect is applied to said razor blade 21 tending to rotate the same in such direction that the cutting edge thereof is positively held in sharpening position, i. e., in engagement with the sharpening roller 27. At this time, the ribs 7a, 8a extend freely within the respective recesses 21c of the razor blade 21.

The construction comprising the slots 5a and 26a together with the biasing arrangements for the pintles 27a permits the sharpening roller 27 to take the position which the razor blade 21 tends to impose thereon when the latter is held in sharpening position under the influence of the spring 12. Thus, by reference to Fig. 6 and assuming that the pintles 27a have been moved upwardly to the ends of the respective slots provided therefor, the line L may be taken as designating the longitudinal axis of the sharpening roller 27 and its pintles 27a. If the sharpening roller 27 should be so mounted that this longitudinal axis is incapable of adjustment, it would be necessary for the longitudinal axis of the detents 17 and 18, the extreme end of the cutting edge of the razor blade 21 and said longitudinal axis L to be disposed exactly in parallel relation if said cutting edge last named is to effectively engage the sharpening roller 27 throughout the length thereof. This parallel relation is difficult to obtain in ordinary manufacturing operations.

As indicated in Fig. 6, it may be assumed that the longitudinal axis of the detents 17 and 18 or the extreme cutting edge of the razor blade 21 is parallel to a line L instead of the line L. Under these conditions, if the longitudinal axis of the sharpening roller 27 and its pintles 27a were fixed, there would be a gap between the end of the razor cutting edge at the right, Fig. 6, and the roller 27, and this gap would extend from right to left, Fig. 6, throughout almost the entire length of the razor blade 21. However,

since the longitudinal axis of the sharpening roller 27 and its pintles 27a is adjustable as described, the line L does not remain in the position shown but it does take a position wherein it coincides with the line L1. As a result, the razor cutting edge engages said sharpening roller 27 throughout its entire length and, therefore, the sharpening operation may be efficiently and properly performed.

10 As stated above, when it becomes desirable to sharpen the razor blade 21, the yoke 16 is elevated with respect to the frame 3 until the square rod section 16 clears the square passage 15 whereupon the handle sleeve 11 is rotated through an angle of 180 degrees while holding the circular gripping section stationary. Obviously, an operation the reverse of that described is performed when it becomes desirable to move the razor blade 21 from the sharpening position to shaving position.

20 A feature of the invention resides in the fact that the described mechanism is adapted for readily sharpening both sides of the blade 21. Thus, after one side of said blade 21 has been sharpened as described above, the yoke 16 may be elevated and so held while the blade 21 is rotated on the detents 17, 18 through an angle of more than 180 degrees to bring the sharpened blade surface uppermost. Thereupon, the yoke 16 is rotated through an angle of 180 degrees and reseated in operative position on the frame 3. This brings the non-sharpened surface of the blade 21 into engagement with the sharpening roller 27.

25 The construction comprising the square rod 14 and the square passage 15 is of importance because, provided that this rod and passage have the proper longitudinal dimensions, it will be necessary to elevate the yoke 16, in order to have the square rod 14 clear the square passage 15, to such extent that the edge of the blade 21 cannot engage any part of the frame 3 including the plates 5, 5 with consequent damage thereto during the described rotatable movement of said 30 blade 21 which is imposed thereon when the yoke 16 is rotated with respect to the tubular member 1 and the frame 3. In this connection, it is to be noted that the mechanism comprising the detents 17 and 18, which pivotally support the razor blade 21 on the yoke 16, prevents movement of said razor blade 21 with respect to the yoke when the latter is elevated to move the razor blade away from either the cam member 24 or the sharpening roller 27 as the case may be.

35 In accordance with the invention, the vertical sides of the yoke sections 16b closely engage the respective vertical sides of the plate recesses 9. By virtue of this arrangement, the yoke 16, when the razor blade 21 is either in shaving or sharpening position, is positively prevented from rotatably moving with respect to the tubular member 1 and the frame 3. Thus, no side-sway of the razor blade occurs during the sharpening or shaving operations. With the described relation 40 between the yoke sections 16b and the plate recesses 9, the fit between the square rod 14 and square passage 15 may be loose or inaccurate.

45 As will be understood, when the razor is held in one hand, the thumb of that hand is conveniently located for actuating the cam member 24 to change the elevation of the razor blade 21. As shown in Fig. 7, the plate 6 may have graduations thereon, the pointed handle 24a coacting with these graduations to indicate different degrees of adjustment. In connection with the

cam member 24, it will be noted that it is mounted on the plate 6 as described above. This plate 6 serves as a barrier preventing or impeding the admission of soap, etc., into the rear of the razor, i. e., the sharpening side thereof. The plate 6 also serves to strengthen the frame 3.

While the rod section 14 and the passage 15 have been described as square in cross-section, it will be understood that this rod section and passage may be triangular or otherwise of polygonal cross-section. In the appended claims, the term "polygonal" shall be given this generic meaning.

Referring to Fig. 9, I have shown an assembly comprising a yoke 16 and a razor blade 21 of the character hereinbefore described. In lieu of the mechanism shown in Fig. 8 for detachably securing the razor blade to the yoke, I have shown in Fig. 9 rivets or bolts 32 which are utilized for permanently securing the arms 21a of the razor blade to the respective yoke arms. It is intended that assemblies as shown in Fig. 9 shall be stocked in retail stores or the like so that the owner of the complete razor, when the blade thereof becomes unsuitable for further use, may remove the blade and yoke assembly and substitute a new assembly therefor.

While the invention has been described with respect to a certain particular preferred example which gives satisfactory results, it will be understood by those skilled in the art after understanding the invention, that various changes and modifications may be made without departing from the spirit and scope of the invention and it is intended therefore in the appended claims to cover all such changes and modifications.

What is claimed as new and desired to be secured by Letters Patent is:

1. In a combined razor and sharpening device, supporting means for a razor blade, means for positioning the edge of the razor blade in shaving position, sharpening means, means for moving said supporting means to cause the razor blade to engage either the positioning means or the sharpening means, and means independent of said sharpening means for engaging the razor blade, when in shaving position, to cause it to be biased against said positioning means.

2. In a combined razor and sharpening device, supporting means for a razor blade, means for positioning the edge of the razor blade in shaving position, sharpening means, means for moving said supporting means to cause the razor blade to engage either the positioning means or the sharpening means, and means independent of said positioning means for engaging the razor blade, when in sharpening position, to cause it to be biased against said sharpening means.

3. In a razor, a frame, a support movable with respect to said frame, means for pivotally mounting a razor blade of the single edge type on said support, means for positioning the edge of the razor blade in shaving position, sharpening means, stop means carried by said frame in spaced relation with respect to said sharpening means, and a spring tending to move said support to a normal position with respect to said frame whereby the front part of said razor blade is held in engagement with said positioning means and the rear part of said razor blade is held in engagement with said stop means, said spring and said stop means cooperating to hold the razor blade firmly against said positioning means.

4. In a razor, a frame comprising side plates,

a support movable with respect to said frame, means for pivotally mounting a razor blade of the single edge type on said support, means for positioning the edge of the razor blade in shaving position, stop means comprising members carried by the respective side plates of said frame and disposed in transverse alignment, and a spring tending to move said support to a normal position with respect to said frame whereby the

5 front part of said razor blade is held in engagement with said positioning means and the rear part of said razor blade is held in engagement with said members, said spring and said members cooperating to hold the razor blade firmly 10 against said positioning means.

5. In a razor, a frame, a support movable with respect to said frame, means for pivotally mounting a razor blade of the single edge type on said support, sharpening means, means for positioning

20 the edge of the razor blade in shaving position, stop means carried by said frame in spaced relation with respect to said positioning means, and a spring tending to move said support to a normal position with respect to said frame whereby

25 the front part of said razor blade is held in engagement with said sharpening means and the rear part of said razor blade is held in engagement with said stop means, said spring and said stop means cooperating to hold the razor blade 30 firmly against said sharpening means.

6. In a razor, a frame comprising side plates, a support movable with respect to said frame, means for pivotally mounting a razor blade of the single edge type on said support, sharpening means, means for positioning

35 the edge of the razor blade in shaving position, stop means comprising members carried by the respective side plates of said frame and disposed in transverse alignment, and a spring tending to move said support to a normal position with respect to said frame whereby the front

40 part of said razor blade is held in engagement with said sharpening means and the rear part of said razor blade is held in engagement with said members, said spring and said members cooperating to hold the razor blade firmly against 45 said sharpening means.

7. In a razor, a frame, a support movable with respect to said frame, means for pivotally mounting a razor blade of the single edge type on said

50 support, means for positioning the edge of the razor blade in shaving position, sharpening means, said positioning means and said sharpening means being disposed at the respective opposite sides of the pivotal mounting for said razor blade, stop means carried by said frame between said sharpening means and said pivotal mounting for the razor blade, and a spring tending to move said support to a normal position with respect to said frame whereby the front part of said razor

55 blade is held in engagement with said positioning means and the rear part of said razor blade is held in engagement with said stop means, said spring and said stop means cooperating to hold the razor blade firmly against said positioning 60 means.

8. In a razor, a frame, a support movable with respect to said frame, means for pivotally mounting a razor blade of the single edge type on said support, means for positioning the edge of the

70 razor blade in shaving position, sharpening means, said positioning means and said sharpening means being disposed at the respective opposite sides of the pivotal mounting for said razor blade, stop means carried by said frame between said positioning means and said pivotal

75

mounting for the razor blade, and a spring tending to move said support to a normal position with respect to said frame whereby the front part of said razor blade is held in engagement with said sharpening means and the rear part of said razor blade is held in engagement with said stop means, said spring and said stop means cooperating to hold the razor blade firmly against said sharpening means.

9. In a razor, a tubular support, a frame carried at one end thereof, a rod structure slidable in said tubular support, a support carried by said rod structure for mounting a razor blade, and a spring effective between said rod structure and said tubular support, said rod structure comprising a section which is polygonal in cross-section, said polygonal section being held by said spring in a passage in said tubular support which is polygonal in cross-section, the rod structure and the support for said razor blade being movable against the action of said spring to a position wherein said polygonal section clears said polygonal passage whereupon the razor blade and its support may be rotated with respect to said frame.

10. In a razor, a tubular support, a frame carried at one end thereof, a rod structure slidable in said tubular support, a handle carried by said rod structure, a support carried by said rod structure for pivotally mounting the razor blade, a spring effective between said rod structure and said tubular support, said rod structure comprising a section which is polygonal in cross-section, said polygonal section being held by said spring in a passage in said tubular support which is polygonal in cross-section whereby said razor blade is maintained in one position, the rod structure, the handle and the support for said razor blade being movable against the action of said spring to a position wherein said polygonal section clears said polygonal passage whereupon the razor blade and its support may be rotated with respect to said frame to move said razor blade to another position, and means independent of said polygonal section and passage for positively retaining the rod structure, the handle and the support in different respective positions wherein the razor blade occupies either its first named position or its second named position.

11. In a razor, a tubular support, a frame carried at one end thereof, a rod structure slidable in said tubular support, a handle carried by said rod structure, a support carried by said rod structure for pivotally mounting the razor blade, a spring effective between said rod structure and said tubular support, said rod structure comprising a section which is polygonal in cross-section, said polygonal section being held by said spring in a passage in said tubular support which is polygonal in cross-section whereby said razor blade is maintained in one position, the rod structure, the handle and the support for said razor blade being movable against the action of said spring to a position wherein said polygonal section clears said polygonal passage whereupon the razor blade and its support may be rotated with respect to said frame to move said razor blade to another position, and means independent of said polygonal section and passage for positively retaining the rod structure, the handle and the support in different respective positions wherein the razor blade occupies either its first named position or its second named position, said means comprising oppositely extending sections disposed, respectively, in recesses formed in said frame.

12. In a razor, a frame, means for pivotally mounting a razor blade for movement with respect to said frame, a guard secured to said frame, a plate extending across said frame, and a cam plate secured flatwise against said plate for varying the angle of inclination of said razor blade and for changing the position of the shaving edge thereof with respect to said guard.

13. In a razor, a tubular support, a frame carried at one end thereof, a rod structure slidable in said tubular support, a support carried by said rod structure for mounting a razor blade, and a spring effective between said rod structure and said tubular support, said rod structure comprising a section which, when held by said spring in a passage of said tubular support, prevents rotation of said rod structure and said tubular support with respect to each other, the rod structure and the support for said razor blade being movable against the action of said spring to a position wherein said section clears said passage whereupon the razor blade and its support may be rotated with respect to said frame.

14. In a razor, a tubular support, a frame carried at one end thereof, a rod structure mounted in said tubular support for rotatable and axial movement with respect thereto, a support carried by said rod structure for mounting a razor blade, a spring effective between said rod structure and said tubular support for seating the razor blade support on said frame with said razor blade occupying one position, the rod structure and the razor blade support being movable axially of said tubular support against the action of said spring, and means preventing rotatable movement of the rod structure and the razor blade support with respect to said tubular support until such axial movement has proceeded sufficiently to render the razor blade incapable of striking said frame during rotatable movement thereof to a new position angularly spaced from said first position by 180 degrees.

15. In a razor, a frame, a support movable with respect to said frame, means for pivotally mounting a razor blade of the single edge type on said support, said razor blade, on the respective opposite sides thereof, having transversely aligned recesses formed therein, means for positioning the edge of the razor blade in shaving position, stop means comprising two pairs of transversely aligned members carried by said frame, and a spring tending to move said support to a normal position with respect to said frame whereby the front part of said razor blade is held in engagement with said positioning means and the rear part of said razor blade is held in engagement with one pair of said members, the other pair of said members being received in the respective recesses of said razor blade, said spring and said one pair of members cooperating to hold the razor blade firmly against said positioning means.

16. In a razor, a frame, a support movable with respect to said frame, means for pivotally mounting a razor blade of the single edge type on said support, said razor blade, on the respective opposite sides thereof, having transversely aligned recesses formed therein, sharpening means, stop means comprising two pairs of transversely aligned members carried by said frame, and a spring tending to move said support to a normal position with respect to said frame whereby the front part of said razor blade is held in engagement with said sharpening means and the rear part of said razor blade is held in engagement

with one pair of said members, the other pair of said members being received in the respective recesses of said razor blade, said spring and said one pair of members cooperating to hold the razor blade firmly against said sharpening means.

17. In a razor, a yoke having a pair of parallel arms, a razor blade having a pair of parallel arms disposed in embracing and interfitting relation with the yoke arms, and a pivot for connecting each yoke arm to the adjacent razor blade arm, the pivots being disposed parallel with the cutting edge of the razor blade.

18. In a razor, a yoke having a pair of parallel arms, a razor blade having a pair of parallel arms disposed in interfitting relation with the yoke arms, and a detent for connecting each yoke arm to the adjacent razor blade arm, spring means for biasing the detents from each other, and a pin associated with each detent, the pins being moved toward each other when it becomes desirable to release the razor blade from the yoke.

10

RAY L. BURCHETT.
